METALLIC EXPANDED TREAD

Charles L. Moorman, Millington, Ill.

Application January 21, 1949, Serial No. 370

Term of patent 14 years

(Cl. D9—6)

To all whom it may concern:

Be it known that I, Charles L. Moorman, a citizen of the United States and a resident of Millington, in the county of Kendall and State of Illinois, have invented a new, original, and ornamental Design for a Metallic Expanded Tread, of which the following is a specification, reference being had to the accompanying drawing, forming a part thereof, and in which:

Fig. 1 is a top plan view of a metallic expanded tread, showing my new design;

Fig. 2 is an edge view of the same.

I claim:

The ornamental design for a metallic expanded tread, as shown.

CHARLES L. MOORMAN.
